His Attorney.

UNITED STATES PATENT OFFICE

CHARLES F. DOUGHERTY, OF TULSA, OKLAHOMA, ASSIGNOR TO JOHN J. LARKIN, OF ST. LOUIS, MISSOURI

CASING SHOE ATTACHMENT

Application filed September 2, 1927. Serial No. 217,075.

This invention relates to a device designed for attachment to the end of a well casing and more particularly to the casing shoe as used in oil wells.

5 In the boring of oil wells, more particularly by rotary drills, the casing as let down into the well is provided with a shoe made of steel and of substantial construction. In order to guide the shoe into place, coupled thereto is a guide comprising a hollow head which tapers to its terminal in order to cause the shoe to pass obstructions, this head being of a material such as cast iron, which is friable under the action of a drill in the well, 10 so that the drill can pass therethrough and leave the shoe in place to set on the well bottom. The guide has a terminal opening which is closed by a valve held on its seat at the guide terminal by a spring. This valve 15 not only serves the function of permitting the casing to be floated into the well, but also permitting flushing and washing out of the hole as well as to permit cement to be pumped therethrough in order to cement the casing in 20 place.

Where the valve is at the terminal of the guide, it is liable to strike obstructions, thereby interfering with its operation and even breaking the same. One of the objects of this 25 invention, therefore, is to provide a device of the character described, in which the valve seat is within the head and above the terminal opening, so that this valve will be protected.

30 Another object of this invention is to provide a device of the general character described, the terminal of which is a definite nozzle adapted to direct a stream down into the hole so as to forcibly wash the cavings 35 ahead of the casing.

Another object is to provide a device of the general character described, in which the terminal opening or outlet is susceptible of 40 adjustment to meet requirements in the sinking 45 of a casing and in the cementing thereof.

Further objects will appear from the detail description, taken in connection with the accompanying drawing, in which—

50 Figure 1 is an elevation, partly in section,

showing one embodiment of this invention; and

Figure 2 is a section on the line 2—2 of Figure 1.

Referring to the accompanying drawing, 1 55 designates a casing shoe which may be of the usual construction and which may in some cases be a part of the well casing itself; the casing shoe, where employed, is usually made of steel and of substantial form, being provided at its upper end with threads (not shown) for coupling to a casing and at its lower end with threads to permit coupling thereto of a guide or other device; the end of the shoe may be, as usual, provided with an inclined finished face 2.

The device embodying this invention, one embodiment of which is illustrated, comprises a head having a coupling or neck 3 (in this case shown as reduced with respect to the head) and threaded to take into the shoe; it will be understood, of course, that any other suitable coupling arrangement may be provided. The head itself is of substantial 70 diameter, and has a shoulder 4 co-operating with the face 2 on the shoe. The head tapers from the shoulder to its terminal, which is provided with an opening or outlet, as shown. The head is hollow and, as shown, has a partition 5 integral 75 therewith and providing a valve seat 6 which is arranged to co-operate with a valve 7, the stem 8 of which passes through a guide or bearing 9 on the head. A spring 10 on the valve stem bears against the guide 9 and a 80 nut 11 in order to hold the valve on its seat.

As shown, the head terminates in a nozzle 12 having a gradually reduced opening 13 which converges from the inside tapering 85 surface of the head in rounded form to conform to the contraction of the jet as it approaches the nozzle orifice. This nozzle is preferably formed as a separate plug arranged to be screwed into the head so that it 90 may be removed and replaced, the screw threads being shown at 14. There are additional openings 15 arranged around the nozzle opening, each opening being threaded to receive a plug 16, while bosses 17 are provided 95 100

in order to furnish substantial bearings for the plug threads.

It will, therefore, be seen that this invention accomplishes its objects. The valve seat 5 is formed inside of the head so that the seat as well as the valve will be protected to the extent that the wall forming the guiding face furnishes a protecting wall. The head with its valve can, therefore, be used not only as 10 a guide, but also as a float plug, a wash-down plug, and as a cementing plug. Since the head can be made of cast iron, it is sufficiently friable under the action of a drill in the well that it can be bored out and the 15 cuttings discarded without interfering with further operations.

The nozzle 12 provides means whereby a stream can be directed down into the hole in order to wash the cavings ahead of the 20 casing, and to wash out the bottom of the hole so that the casing can be let down. The somewhat elongated shape of the inside faces 13 particularly permits of a strong solid concentrated stream being forced down the hole.

25 When required, the opening in the bottom of the head can be adjusted or enlarged either by the removal of one or more plugs 16, and to a considerable extent, by the removal of the nozzle plug 12. Accordingly, this device is adapted to a variety of conditions 30 encountered in the boring and sinking of casings in oil and gas wells.

While the invention is particularly applicable in the relation shown, it will be understood that it is applicable in many cases 35 in other relations. It will, furthermore, be understood that certain features and sub-combinations are of utility and may be employed without reference to other features, 40 operations and sub-combinations; that is contemplated by and is within the scope of the appended claims. It is, furthermore, obvious that various changes may be made in details, within the scope of the appended 45 claims, without departing from the spirit of this invention. It is, therefore, to be understood that this invention is not to be limited to the specific details shown and/or described.

Having thus described the invention, what 50 is claimed is:

1. A device designed for attachment to the end of a well casing shoe to extend therebeyond when attached to provide a guide therefor, comprising, a hollow head having at one 55 end a coupling, the projecting portion of said head having a tapered rim portion adapted to provide a casing guide, an elongated wide-mouthed nozzle beyond said rim portion at the tip of said head adapted to project a 60 strong concentrated stream down into the hole, a plurality of auxiliary jet outlets adjacent said nozzles, and removable closures for said outlets.

65 2. A device designed for attachment to the end of a well casing shoe to extend thereb-

yond when attached to provide a guide therefor, comprising, a hollow head having at one end a coupling, the projecting portion of said head having a tapered rim portion adapted to provide a casing guide, an elongated wide-mouthed nozzle at the tip of said head adapted to project a strong concentrated stream down into the hole, a plurality of auxiliary jet outlets adjacent said nozzle, removable closures for said outlets, and a float valve in 70 said head.

3. A device designed for attachment to the end of a well casing shoe to extend therebeyond when attached to provide a guide therefor, comprising, a hollow head having at one end a coupling, the projecting portion of said head having a tapered rim portion adapted to provide a casing guide, an elongated wide-mouthed nozzle removably fitted in the tip of said head adapted to project a strong concentrated stream down into the hole, a plurality of auxiliary jet outlets adjacent said nozzle, and removable closures for 80 said outlets.

4. A device designed for attachment to the end of a well casing shoe to extend therebeyond when attached to provide a guide therefor, comprising, a hollow head having at its upper end a reduced threaded neck adapted to couple with a shoe, the head below said neck being tapered inwardly and downwardly to provide a guide, a partition in said head below said neck and provided with a seat, a valve engaging said seat and having an upwardly extending stem, and a bearing for said stem mounted in said neck above said partition.

5. A device designed for attachment to the end of a well casing shoe to extend therebeyond when attached to provide a guide therefor, comprising, a hollow head having at its upper end a reduced threaded neck adapted to couple with a shoe, the head below said neck being tapered inwardly and downwardly to provide a guide, a partition in said head extending inwardly and downwardly below said neck and provided with a seat, a valve engaging said seat and having an upwardly extending stem, and a bearing for said stem mounted in said neck above said partition.

6. A device designed for attachment to the end of a well casing shoe to extend therebeyond when attached to provide a guide therefor, comprising, a hollow head having at its upper end a reduced threaded neck adapted to couple with a shoe, the head below said neck being tapered inwardly and downwardly and having a nozzle at its lower end, a partition in said head below said neck and provided with a seat, a valve engaging said seat and having an upwardly extending stem, and a bearing for said stem mounted in said neck above said partition.

7. A device designed for attachment to the end of a well casing shoe to extend thereb-

yond when attached to provide a guide there-
for, comprising, a hollow head having at its
upper end a reduced threaded neck adapted to
couple with a shoe, the head below said neck
5 being tapered inwardly and downwardly and
having a nozzle at its lower end, a partition
in said head extending inwardly and down-
wardly below said neck and provided with a
seat, a valve engaging said seat and having
10 an upwardly extending stem, and a bearing
for said stem mounted in said neck above said
partition.

In testimony whereof I affix my signature
this 22nd day of July, 1927.

15 CHARLES F. DOUGHERTY.
